Primary Examiner — Elizabeth Albert(74) *Attorney, Agent, or Firm* — Lerner, David, Littenberg, Krumholz & Mentlik, LLP(57) **CLAIM**

The ornamental design for a hole punch, as shown and described.

DESCRIPTION

FIG. 1 is a front view of a hole punch showing my new design;
 FIG. 2 is a rear view of FIG. 1;
 FIG. 3 is a top view of FIG. 1;
 FIG. 4 is a bottom view of FIG. 1;
 FIG. 5 is a right side view of FIG. 1;
 FIG. 6 is a left side view of FIG. 1;
 FIG. 7 is a front perspective view of FIG. 1;
 FIG. 8 is a rear perspective view of FIG. 1;
 FIG. 9 is a front view of FIG. 1 shown in an open position;
 FIG. 10 is a rear view of FIG. 9;
 FIG. 11 is a top view of FIG. 9;
 FIG. 12 is a bottom view of FIG. 9;
 FIG. 13 is a left side view of FIG. 9;
 FIG. 14 is a right side view of FIG. 9;
 FIG. 15 is a front perspective view of FIG. 9; and,
 FIG. 16 is a rear perspective view of FIG. 9.

The surfaces or portions of the hole punch shown in the drawings in broken lines form no part of the claimed design.
